LEONARD TILTON, OF BROOKLYN, E. D., NEW YORK.

Letters Patent No. 65,303, dated May 28, 1867.

IMPROVEMENT IN WOOD-SPLITTING MACHINES.

The Schedule referred to in these Letters Patent and making part of the same.

TO ALL WHOM IT MAY CONCERN:

Be it known that I, LEONARD TILTON, of Brooklyn, Kings county, New York, have invented a new and improved Machine for Splitting Wood; and I do hereby declare that the following is a full, clear, and exact description thereof, which will enable others skilled in the art to make and use the same, reference being had to the accompanying drawings, forming part of this specification.

This invention relates to a new and improved machine for splitting wood for fire-kindling purposes; and it consists of two reciprocating V-shaped knives, or cutters and a swinging holder, arranged in relation with a hopper, and operated as hereinafter fully shown and described, whereby wood may be split into small or thin square pieces very expeditiously, and with but a moderate expenditure of power.

Figure 1 is a side sectional view of my invention, taken in the line *x x*, fig. 3.

Figure 2, a transverse vertical section of the same, taken in the line *y y'*, fig. 1; and

Figure 3, a plan or top view of the same.

Similar letters of reference indicate corresponding parts.

A represents the framing of the machine, on which there is a slide or an adjustable plate, B, having a shaft, C, fitted transversely upon it at its inner end. On this shaft C there is firmly keyed a cam, D, composed of a circular plate, *a*, having an irregular curved groove, *b*, at one side of it, (see fig. 1.) This groove *b* receives the friction-roller *c* of a bar, E, which has a slide, F, attached to its outer end, said slide working between guide-plates *d d* on the frame A, and having the V-shaped cutters G G' attached to it, one cutter being above the other; but the cutters having a reverse position relatively with each other, as shown clearly in fig. 2. The lower cutter G' projects a little in front of the upper cutter G, as shown in fig. 1, and both cutters work into a hopper, H, through slots *e* in one side thereof. The hopper H is composed of two vertical parts, *ff'*, secured together by set-screws *g*, and the part *f* is connected with the guide-plates *d d*, which, in consequence of being adjustable, admit of the hopper being enlarged in a direction longitudinally with the frame of the machine, to suit the length of the sticks to be split. I represents a swinging frame, suspended on a shaft, J, which is fitted in brackets *h* attached to the upper part of the hopper H. To the lower part of this frame I there is secured a holder, K, of V-form, like the cutters G G', and having its angle uppermost like the lower cutter G'. One side of the frame I has a rod, L, connected to it, and said rod passes loosely through an arm, M, which projects laterally from the slide F. The rod L has two adjustable knobs, *e e'*, upon it, one at each side of the arm M; and between the arm M and the knob *e'* on rod L a spiral spring, N, is placed, as shown clearly in fig. 3.

The operation is as follows: The wood to be split is sawed into pieces of a suitable length and placed in the hopper H so that its grain will have a horizontal position, and be in line with the cutters G G' when the latter are acting upon it. The cam-groove *b* is of such a shape that it will move the cutters G G' to their work slowly, and move them back quickly, considerable power being required in former case, and little power required in the latter case. The upper cutter G, being shorter than the lower one G', simply checks the wood or stick, and the lower one splits the pieces entirely off from the wood or stick. When the cutters G G' are drawn back out from the hopper H, the wood or stick is held or supported by the holder K, which is swung or brought under the hopper H by the backward movement of the slide F, the rod L forming the connection between the slide F and the holder-frame I, and the spring N admitting of the slide F completing its backward movement without causing the rod L to be drawn in any appreciable degree upon the frame I after the latter has arrived at a vertical position, and the holder K brought underneath the hopper to support the wooden stick within it. In consequence of the cutters G G' having a reverse position relatively with each other, and one cutter being placed above the other, as shown, the cuts of the lower cutter G' intersect the cuts of the upper cutter, and the wooden stick will be split into small square pieces, the holder K, when underneath the hopper, being a short distance below the line of movement of the lower cutter G', and the dropping of the wood or stick upon the holder K on the withdrawal of the cutters from the hopper constituting the feed movement. The shortening of the cutters G G' by wear is compensated for by adjusting the plate B forward, the latter being held in position by set-screws *a'*, (see fig. 3.) The adjustable guide-plates *d d* are also held in position by set-screws *b'*.

I claim as new, and desire to secure by Letters Patent—

1. The two reciprocating cutters G G' of V-form, placed one above the other in reverse positions, and the lower cutter G' in advance of the upper one G, substantially as and for the purpose set forth.
2. The hopper H, in combination with the cutters G G' and the holder K, substantially as and for the purpose specified.
3. Operating the holder K from the slide F, to which the cutters are attached by means of the rod L, connected with the slide, as shown, and the spring N, as set forth.
4. Constructing the hopper H of the vertical parts f f', one of which, f, is adjustable, for the purpose of adapting the hopper to suit the length of the sticks to be split, as shown and described.

The above specification of my invention signed by me this 13th day of March, 1867.

LEONARD TILTON.
